UNITED STATES PATENT OFFICE

164,070

SEWING CABINET

Gertrude K. Stecher, Grosse Pointe Farms, Mich.

Application May 6, 1950, Serial No. 9,755

Term of patent 7 years

(Cl. D3—19)

To all whom it may concern:

Be it known that I, Gertrude K. Stecher, a citizen of the United States, residing at Grosse Pointe Farms, county of Wayne, in the State of Michigan, have invented a new, original, and ornamental Design for a Sewing Cabinet, of which the following is a specification, reference being made to the accompanying drawing, forming part thereof.

Fig. 1 is a top plan view of a sewing cabinet embodying my design.

Fig. 2 is a side elevational view thereof.

Fig. 3 is an end view thereof.

I claim:

The ornamental design for a sewing cabinet, as shown,

GERTRUDE K. STECHER.
